UNITED STATES PATENT OFFICE.

ROBERT H. BROWN, OF ELK RIDGE LANDING, MARYLAND.

DESIGN FOR A SHOW-BOX FOR BOTTLES.

SPECIFICATION forming part of Design No. 14,252, dated September 4, 1883.

Application filed August 1, 1883. Term of patent 3½ years.

To all whom it may concern:

Be it known that I, ROBERT H. BROWN, a citizen of the United States, residing at Elk Ridge Landing, in the county of Howard and State of Maryland, have invented and produced a new and original Design for Show-Boxes for Bottles, of which the following is a specification, reference being had to the accompanying drawing, forming a part hereof.

10 The said drawing is a perspective view of my newly-designed show-box.

The leading features of my design consist in spreading a series of shelved columns on either side of the bottom, at different angles of inclination, so as to produce a fan-like effect, in having a solid projecting column for the back, and in placing between the inclined columns and in front of the projecting back a rectangular base, upon which is erected a statuette.

15 Further, the projecting back is provided with lateral wings of an angular cross-section, the angles facing toward the front.

A is the bottom of the box, and B a rectangular base seated thereon. C is a statuette resting upon the base B. D D are inclined 25 shelved columns, arranged after the design of a fan. E is the solid projecting back, and F F are the lateral wings with the shelves for sustaining bottles.

It will be understood that the design is for 30 the box when opened, so as to display its contents.

I claim—

The design for a show-box for bottles herein shown and described, the same consisting of 35 the base B, inclined columns D, arranged after the design of a fan, projecting or solid back E, the lateral wings F, having an angular cross-section, with the angles facing the front, and the statuette C.

ROBERT H. BROWN.
